UNITED STATES PATENT OFFICE.

WALTER R. GRISSEL AND HENRY S. JOSSELYN, OF CEDAR RAPIDS, IOWA.

PLATE-GLASS SETTING.

981,189.

Specification of Letters Patent. Patented Jan. 10, 1911.

Application filed April 11, 1910. Serial No. 554,771.

To all whom it may concern:

Be it known that we, WALTER R. GRISSEL and HENRY S. JOSSELYN, citizens of the United States of America, residing at Cedar 5 Rapids, in the county of Linn and State of Iowa, have invented certain new and useful Improvements in Plate-Glass Settings, of which the following is a specification, reference being had therein to the accompanying drawing.

This invention relates to improvements in plate glass settings, and has for its primary object to provide a setting which will permit of the plate glass being placed in position from the outside of the building, and thereby greatly facilitate the setting of plate glass in position.

Another object of the invention is to provide means whereby to effectually resist the heavy wind pressure to which large glass plates are subjected and to reduce to a minimum the danger of the plate glass being broken under such pressure.

With the above broad objects in view, and other minor ones which will appear as the invention is more fully described, the invention consists in the novel construction, combination and arrangement of parts as will be hereinafter described and then particularly claimed.

In describing the invention in detail, reference will be had to the accompanying drawings forming a part of this application and wherein like numerals of reference will be employed to indicate like parts throughout the different views in which:

Figure 1 is an elevation of a window partly broken away and illustrating the application of our improved setting thereto. Fig. 2 is a detail sectional view taken on the line 2—2 of Fig. 1. Fig. 3 is a similar view taken on line 3—3 of Fig. 1. Fig. 4 is a detached view in rear elevation of a part of one of the securing strips for the plate glass, and, Fig. 5 is a bottom view of the same.

In the drawings, 10 designates the frame of the window, which, in order to accommodate a setting constructed in accordance with our invention is provided with an outwardly-extending off-set or strip 11 extending at right angles to the frame 10, and fixedly secured thereto. This off-set or strip is of considerably less width than the frame 10, thereby providing a recess all around the window frame, and the outer face of

the frame as well as the outer face of the strip or off-set 11 is provided with a sheet metal facing 12 bent to conform to the strip or off-set 11 and the frame 10, as best seen in Figs. 2 and 3.

Along the outer edge of the frame formed by the members 10 and 11 is placed a corrugated metal strip 14, against which the plate glass 15 rests, when in position. The plate glass 15 is preferably supported along its lower edge by supporting blocks 16 which in practice, we have preferably made from sheets of lead, the same forming a very desirable as well as cheap support for the glass. The opening in the frame which receives the glass is made somewhat larger than the dimensions of the glass plate, and in practice we have made said opening of a size so that there will be a space of substantially an inch all around the glass between the edges thereof and the face of the member 11. The glass plate is held in position by means of securing strips 17 formed of sheet metal, and which in practice are so shaped as to provide a face plate to represent any desired molding or beading. These strips 17 are secured to blocks 18 by means of which the shape of the strips is retained and through which are passed the hold-fast devices 19 by which the securing strips are firmly attached to the frame. The said strips are each turned inwardly along its outer edge to form an underlying portion spaced from the face plate and provided substantially mid-way its width with a longitudinally-extending rib 20 which engages the outer face of the glass plate 15 at a point in line with the corrugated strip 14. The blocks 18 are placed within the securing strip 17 at intervals, usually about a foot apart, being so shaped as to conform to the face plate with a portion projecting into the space between the face plate and the underlying portion and between these blocks the securing strip at its rear edge is provided with a struck-in portion 21. Secured to the under face of the securing strip are baffle plates 22 which extend beyond each end of the struck-in portions 21. The struck-in portions of the securing strip provide openings 23, which, along the top and the sides of the plate glass serve as ventilators, while those along the bottom of the glass plate serve as drip openings, by means of which all condensation which falls to the bottom of the window may be drained off. The

110

outer edges of the baffle plates 22 are in line with the rear edges of the strips 17, and these baffle plates being placed directly below the openings 23, tend to prevent a free suction of dust into the building through the ventilating and drip openings 23.

- The blocks 18 may be made of any desired material, and on their inner faces are preferably provided with recesses in which 10 are seated rubber or other resilient blocks 24, through which the hold-fast devices 19 are passed, the said resilient blocks or buffers 24 extending a slight distance beyond the inner faces of the blocks 18 and resting 15 against the metal facing 12. By this construction it will be observed that the plate glass is yieldingly seated to resist inward pressure, the corrugated metal strips 14 yielding under pressure which would force the 20 glass inwardly, and the glass is also yieldingly seated against any outward pressure, the rib 20 yielding under such pressure. Since the strips 17 are also yieldingly mounted owing to the provision of the buffers 24, it will be observed that the hold-fast devices may be firmly turned home, the buffers 24 compressing under the tightening of the hold-fast devices, and the longitudinal rib 20 of the strip 17 flattening under 25 such compression, without exerting undue pressure on the plate glass 15, and the latter being securely held between the said longitudinal rib 20 and the corrugated strip 14.
- 30 It is well known that the strain upon heavy glass plates such as are used in show windows and the like is from the outside, and it will be observed that in our improved setting, the glass is yieldingly held, allowing it to resist sufficiently under said pres-

sure so as to prevent breaking, and danger of the glass breaking during its return movement when the pressure is relieved is also entirely obviated by reason of the yielding means employed for securing the glass in 45 position.

What we claim is:

1. In a plate glass setting, the combination with a frame to receive the plate glass, of a yieldingly-mounted securing strip binding the glass at its edges to the frame, said strip formed of sheet metal bent to form a face plate and a backwardly-bent outer edge underlying the face plate and spaced therefrom, said underlying portion provided with a rib to engage the plate glass, strengthening blocks with which the face plate of said strip engages between the face plate and the underlying portion of the strip, and securing means passing through the strip and 50 blocks and into the frame.

2. In a plate glass setting, the combination with a frame, of a securing strip formed of sheet metal bent to form a face plate and an underlying portion spaced from the face plate, said underlying portion having a rib intermediate its edges, strengthening blocks against which the face plate rests and having portions projecting into the space between the face plate and the underlying 65 portion of the strip, and means for securing the strip and blocks to the frame.

In testimony whereof we affix our signatures in the presence of two witnesses.

WALTER R. GRISSEL.
HENRY S. JOSSELYN.
